VAPOR ELECTRIC DEVICE

Walter Damitz, Berlin-Siemensstadt, Germany,
assignor to Siemens-Schuckertwerke Aktien-
gesellschaft, Berlin-Siemensstadt, a corpora-
tion of Germany

Application December 9, 1937, Serial No. 178,943
In Germany December 12, 1936

6 Claims. (Cl. 250—27.5)

My invention relates to a vapor-electric device, and particularly to a combination make-alive mounting and spot fixing device.

In the operation of vapor-electric devices controlled by make-alive electrodes, it is desirable to maintain the make-alive electrode with a portion thereof extending for a predetermined distance into the vaporizable reconstructing cathode material. However, because of the vaporizable nature of the material, the make-alive electrode, if permanently fixed, will extend into the cathode various amounts during different stages of operation because of the variation in the level of the cathode material, due to evaporation and the slowness of the return of the condensed cathode material. Also, it has been found desirable, in such devices, particularly in mercury-arc rectifiers, to provide a spot fixing body to which the cathode spot can attach in order to reduce the amount of cathode material evaporated into the arc space.

According to my invention, a predetermined immersion of the make-alive electrode at any stage of the cathode level, as well as the provision of a spot fixing body, is accomplished by providing a raft or float resting on the surface of the cathode material, at least a portion of the float being constructed of a material capable of permitting the attachment of a cathode spot without undue deterioration. The float or spot fixing body has attached thereto a suitable bracket or support for maintaining the make-alive electrode in a predetermined relation to the surface of the cathode material, suitable connection being provided for supplying current to the make-alive electrode.

It is an object of my invention to provide a float for supporting a make-alive electrode in a predetermined relation to the surface of the cathode of a vapor-electric device.

It is a further object of my invention to provide an electrode support which acts as a spot fixing body for the attachment of the cathode spot in an arc type discharge device.

It is a further object of my invention to provide an electrode support so arranged as to prevent undue agitation of the surface of the cathode material because of the attachment of the cathode spot thereto.

Other objects and advantages of my invention will be apparent from the following detailed description taken in conjunction with the accompanying drawing, in which:

Figure 1 is a sectional elevation of a vapor-electric device embodying my invention;

Fig. 2 is a sectional elevation of a modified form of support; and

Figs. 3 and 4 are plan views of the rafts disclosed in Figs. 1 and 2.

In the illustrative embodiment of my invention according to Figure 1, the converter comprises a suitable container 1 herein illustrated as of vitreous material, but which can obviously be of either metal or ceramic material, according to the size and service for which the converter is intended. A suitable anode 2 is sealed into the top of the converter chamber 1 and co-operating with the anode 2 is a cathode 3 of vaporizable reconstructing material, that is, the cathode 3 is composed of a material which will evaporate to provide the working vapor of the converter, which vapor will be condensed and returned to the cathode to maintain the volume substantially constant under any given operating condition. However, it is known that during operation relatively large amounts of the cathode material are evaporated and are present in the container 1 either as operating vapor or as condensed droplets on various portions of the container wall. For this reason, the level of the cathode material fluctuates in response to the operating condition of the converter.

Since it is desirable to maintain the make-alive electrode at a constant partial immersion in the cathode material, in order to maintain substantially constant operating conditions at all times, I have provided a raft 4 which may be made of any suitable material, such as iron, quartz, porcelain or the like, for supporting the make-alive electrode 5 in a predetermined relation to the cathode surface. As illustrated, the make-alive electrode 5 is preferably provided with a tapered point 6 so that the minor fluctuations of the mercury surface will not materially change the operating characteristic.

The make-alive electrode 5 is connected to the raft 4 in any suitable manner. Herein, I have illustrated the make-alive electrode 5 as being clamped to a portion 7 of the raft 4 resembling a bracket. However, it is obvious that a threaded connection could be provided between the bracket 7 and the make-alive electrode 5, or any other suitable fastening be utilized.

Preferably, the float 4 is made in the form of an annular body having a relatively large surface contacting with the surface of the cathode material so that it acts as a damper to damp out any oscillations or waves produced on the cathode surface by the attachment of the cathode spot thereto. I also prefer to provide at least

a portion of the raft or float 4 of a material such as molybdenum, tungsten or other material which is capable of permitting the attachment of the cathode spot without undue deterioration.

5 It will usually be found desirable to prevent the spot fixing body 4 from contacting the walls of the container as in a vitreous or ceramic container, the excess heat conducted to the container wall by the spot fixing body may cause 10 cracking or other damage to the container wall and in the case of a metallic container, contact with the spot fixing body might, in some instances, cause the transfer of the cathode spot from the spot fixing body to the container wall 15 with resulting damage thereto.

In order to anchor the spot fixing raft 4 in the desired portion of the cathode 3, I prefer to provide a suitable guide 10 herein illustrated as an extension of the cathode current lead-in extending 20 upwardly into the cathode material and to provide a suitable cooperating portion on the raft herein illustrated as a collar 11 supported on a dependent bracket 12 for loosely engaging the guide member 10, so that while the raft 4 is free 25 to move in a vertical direction in response to the variation of cathode level, the guide 10 will prevent unnecessary or undesirable lateral motion of the raft 4, so that at all times the spot fixing body 4 and the make-alive electrode 5 supported there- 30 by are maintained in a predetermined position and relation on the surface of the cathode material.

In the modification according to Fig. 2, the float 4 proper is made of ceramic material and has 35 attached thereto a spot fixing body in the form of a sheet metal annulus 15 clamped onto the ceramic float 4 by lugs 16. In certain instances, it may be undesirable to provide an upstanding guide in the cathode material. In such instances, 40 the raft 4 may be maintained in the desired position by constructing the lead-in conductor 20 connected to the make-alive electrode 5 of a material having sufficient rigidity to prevent lateral displacement of the raft 4 or else provided with suitable joints so that the raft 4 is free to move in a 45 vertical direction with the fluctuations of the cathode levels.

While for purposes of illustration I have shown and described specific embodiments of my invention, it will be apparent to those skilled in the art 50 that many changes and modifications can be made therein without departing from the true spirit of my invention or the scope of the appended claims.

I claim as my invention:

55 1. An arc discharge device comprising a container, a plurality of main electrodes therein, one of said main electrodes being of vaporizable re-

constructing material, a make-alive electrode having a portion thereof extending into said cathode during normal operation thereof, a float on said cathode, an annular spot fixing body on said float and means on said float for supporting the 5 make-alive electrode in predetermined relation to said cathode.

2. An arc discharge device comprising a container, a plurality of main electrodes therein, one of said main electrodes being of vaporizable re- 10 constructing material, a make-alive electrode having a portion thereof extending into the cathode material during normal operation thereof, a float on said cathode, an annular spot fixing body on said float, means on said float for supporting the 15 make-alive electrode in predetermined relation to said cathode, and means for limiting the lateral displacement of said float while permitting vertical motion of said float.

3. An electric discharge device comprising an 20 evacuated container, an anode in said container, a cathode of vaporizable reconstructing material, a make-alive electrode having a portion thereof partially immersed in said cathode during normal operation thereof, and means for maintaining the 25 partial immersion of said make-alive electrode at a predetermined point regardless of fluctuation of the level of said cathode material.

4. An electric discharge device comprising an 30 evacuated container, an anode in said container, a cathode of vaporizable reconstructing material, a make-alive electrode having a portion thereof extending into said cathode during normal operation thereof, a raft floating on said cathode material, said make-alive electrode being supported by 35 said raft in predetermined relation to the cathode surface irrespective of the fluctuation of the level of said cathode material.

5. A vapor-electric device comprising an envelope, an anode and a vaporizable cathode there- 40 in, a make-alive electrode extending into the cathode a predetermined distance for controlling said device and a float for maintaining said make-alive electrode in said predetermined relation to said vaporizable cathode.

6. A vapor-electric device comprising an envelope, an anode and a vaporizable cathode there- 45 in, a make-alive electrode extending a predetermined distance into said cathode for controlling said device and said float for maintaining said make-alive electrode in a predetermined relation to said vaporizable cathode, said float having an annular portion in engagement with the surface of the cathode for damping out waves in the cathode material.

WALTER DAMITZ.
